MACHINE FOR MEASURING DIMENSIONS OF SOLID MATERIALS

Jacques A. Pettavel, Geneva, Switzerland, assignor to
Societe Genevoise d'Instruments de Physique, Geneva,
Switzerland, a Swiss firm

Filed Oct. 5, 1961, Ser. No. 66,979

Claims priority, application Switzerland Aug. 4, 1961

Term of patent 14 years

(Cl. D52—6)

FIG. 1

FIG. 2

FIG. 3

FIG. 4

FIG. 5

FIG. 1 is a front perspective view of my machine for measuring dimensions of solid materials,

FIG. 2 is an additional front perspective view of the machine shown in FIG. 1,

FIG. 3 is a rear elevational view of said machine,

FIG. 4 is a top plan view of said machine, and

FIG. 5 is a side elevational view of said machine.

The side opposite FIG. 5 is substantially identical in appearance to the view shown in FIG. 5.

I claim:

The ornamental design for a machine for measuring dimensions of solid materials, as shown and described.
